UNITED STATES PATENT OFFICE.

ALFRED H. CARNES AND RIZAL M. MARR, OF OKEMAH, OKLAHOMA; SAID MARR AS-SIGNOR OF ONE-FOURTH TO SAID CARNES AND ONE-FOURTH TO MRS. J. D. BELFORD, OF OKEMAH, OKLAHOMA.

WORKING BARREL FOR OIL WELLS.

Application filed November 16, 1925. Serial No. 69,416.

The object of the invention is to provide a working barrel of simple construction and yet adapted to completely eliminate the troubles ordinarily encountered in pumping wells 5 where gas is produced from the same sand as the oil and, if allowed to enter the working barrel, will prevent the free seating of the valves; to provide a construction in which the sand will be appropriately trapped to 10 prevent its being drawn into the working barrel on the suction strokes and thus clog up the pumping equipment; to provide for the movement of a larger volume of fluid than normally without the increase in length 15 of stroke of the pump piston or the speed of the pump; and generally to prolong the life of the pumping equipment comprising the valves and their associated parts and the sucker rods and the machinery by which they 20 are operated, thereby cutting down pulling expenses and replacement costs.

With this object in view, the invention consists in a construction and combination of parts of which a preferred embodiment is 25 illustrated in the accompanying drawings, wherein:

Figure 1 is a central vertical sectional view through the invention.

Figure 2 is an enlarged sectional view of 30 the upper end of the working barrel.

Figure 3 is a transverse sectional view on the plane indicated by the line 3—3 of Figure 2.

Figure 4 is an enlarged central vertical 35 sectional view of the working barrel in the region of the standing valve.

Figure 5 is a transverse sectional view on the plane indicated by the line 5—5 of Figure 4.

Figure 6 is an enlarged sectional view just 40 below the plane of the standing valve.

Figure 7 is a similar view of the lower or 45 terminal portion of the working barrel.

Figures 8, 9, 10 and 11 are respectively 50 transverse sectional views on the planes indicated by the lines 8—8, 9—9, 10—10 and 11—11 of Figure 7.

The barrel 20, which is designed for sinking 55 in the well from which the oil is to be removed, is closed at the lower end with a plug 21 and at the upper end receives a coupling member 22 threadingly engaged with the barrel and interiorly threaded for connection with the standing pipe 23. The cou-

pling member 22 is provided with peripheral 55 wickers 24 for engagement with a fishing tool by which the barrel may be removed from the well.

Interiorly to the barrel and engaged at its upper end with the coupling member 22 is 60 the working cylinder 25 which communicates with the standing pipe 23 through the coupling member 22. In the working cylinder is mounted the working valve 26 having the usual suction cups 26^a, the ball valve 26^b and 65 the ball valve cage 26^c. On the downward stroke of the working valve, the contents of the cylinder above the standing valve 27 passes through the working valve, unseating 70 the ball 26^b, thus placing the cylinder contents above the working valve to be elevated by the latter on the upward stroke, the working valve being actuated by a valve rod 28 connected with appropriate operating machinery at the top of the well. 75

The standing valve 27 is of the same general form of the working valve, having the ball 27^a normally closing the opening through the valve and unseating on the upward stroke of the working valve to permit 80 raising the fluid to the working cylinder. The standing valve carries the usual valve cage 27^b to insure the return of the ball 27^a to its seat upon the cessation of such suction. The body of the standing valve 27 is 85 over-size, thus providing a larger opening therethrough than normally, so that a large volume of oil or fluid may be drawn into the working cylinder on the up-stroke of the working valve. 90

The standing valve 27 is connected by means of a coupling 29 with the working cylinder at the lower end of the latter and to the lower end of the standing valve is coupled an intake tube 30 disposed within a separator tube 31 which is connected to the lower end of the body of the standing valve but not in communication with the passage therethrough, as is the intake tube. The lower end of the separator tube extends below the plane of the bottom of the intake tube 30 and connects with a guide cap 32 cut away at its periphery to leave the spaced radial lugs 33 which abut the interior surface of the barrel 20. These lugs maintain the separator pipe centrally disposed with respect to the barrel 20 and the spaces 34 between them and the periphery of the cap 100 105

32 and the interior wall of the barrel provide openings through which the sand may pass to reach the sand trap 35, being the space between the cap 32 and the plug 21.

5 Into the lower end of the plug 21 is inserted an anchor stud 36 which may engage upon the bottom of the well and thus anchor the working barrel to preclude lateral movement in its operation.

10 The separator tube 31 is provided with a plurality of perforations 37 arranged in uniformly spaced vertical series, the lowermost units of which are disposed above the plane of the bottom of the intake tube 30 which is 15 open at its lower end.

When the apparatus is inserted in an oil well, it is lowered until the barrel is completely immersed in the contents, when the oil, with whatever sand it may have gathered, 20 enters the barrel through the openings 38. The combined area of these openings is in excess of the combined area of the perforations 37 in the separator pipe. The oil continues to enter the barrel until it shall have 25 reached a height in the latter to the level of the openings 38. But to reach this level in the barrel, it must also enter the separator tube 31 which it does through the perforations 37, rising in the separator pipe and also

30 in the intake tube 30 which it enters through the bottom end of the latter. Whatever sand may be in the oil will drop by gravity through the openings 34 defined by the lugs 33 and the exterior and interior perforations 35 of the cap 32 and the barrel 20, thus entering the sand trap 35. If the pressure is sufficient, the oil rising through the intake tube 30 will pass the standing valve 27 and enter the working cylinder to be elevated by the 40 working valve through the standing pipe 28.

This arrangement, it will be noted, always provides for oil, free of sand and impurities, being present in the working cylinder and thus the elements of neither the standing 45 valve nor the working valve are subjected to the deleterious effects of these foreign substances. On the up-stroke of the working valve, it always draws on the pure oil in the working cylinder and there no tendency to 50 draw sand in the cylinder since the impurities have been fully settled out prior to the oil entering the intake pipe 30. What gas is present rises to the surface exterior to the working barrel and will therefore not be 55 taken into the working cylinder with its ever-present tendency to keep the valve elements in either the standing or the working valves in unseated positions.

The separator tube 31 above the plane of 60 the perforations 37 and the intake tube 30 are respectively provided with the perforations 39 and 40, so that in the event of the oil supply failing, so that the working barrel may not be supplied to the level of the 65 intake openings 38, the level may never drop

below the plane of the perforations 39 and 40. Should the supply cease for any reason, the working valve will continue to remove the oil until the level in the working barrel shall have dropped to the plane of the perforation 39, after which no further oil may be removed, since the continued operation of the working valve will only result in the intake of air through the openings 38 and the perforations 39 and 40.

The openings 38 have a combined area sufficient to permit the annular space defined by the working barrel and the working cylinder and separator tube being always filled with oil, so long as the producing strata continues to supply a sufficient amount for the work of the pump. This volume of oil constitutes a fluid seal which serves the dual purpose of preventing gas from entering the working barrel and shielding the walls of the well from the effects of the suction of the pump, thereby preventing the sucking-in of the sand with its consequent deleterious effect on the pumping apparatus. What sand enters the working barrel does not do so as a result of suction and provision is made for trapping this as above explained.

The invention having been described, what is claimed as new and useful is:

1. Apparatus comprising a working barrel, a working cylinder housed within the working barrel and being of less diameter than the latter to provide an annular space between the two, an over-size standing valve connected to the lower end of the working cylinder, a working valve operating in the working cylinder, an intake tube connected with the lower end of the standing valve, and a separator tube surrounding the intake tube and having intake openings in communication with the annular space in the working barrel above the plane of the intake of the intake tube, the working barrel having intake openings above the plane of the intake openings of the separator tube and exceeding in area the area of the intake openings of the latter, the separator tube having a cap closing its lower end and the working barrel having a plug closing its lower end and spaced from the cap of the separator tube, the cap of the separator tube having radial lugs abutting the wall of the working barrel and defining openings effecting communication between the annular space in the working barrel and the space below the separator tube cap.

2. Apparatus comprising a working barrel, a working cylinder housed within the barrel and spaced from the walls thereof, standing and working valves housed within the working cylinder, a separator tube, an intake tube enclosed by the separator tube and in communication with the standing valve, the intake tube being open at its lower end, the separator tube extending below the

plane of the lower extremity of the intake tube, a guide cap attached and closing the lower end of the separator tube and having spaced radial lugs abutting the interior wall of the barrel, and a closure attached to the lower end of the working barrel, said closure being spaced from the guide cap, the separator tube having series of lateral perforations above the plane of the lower end of the intake tube and the working barrel having intake openings above the plane of said perforations.

In testimony whereof they affix their signatures.

ALFRED H. CARNES.
